UNITED STATES PATENT OFFICE

DANIEL BELL, OF CHICAGO, ILLINOIS, ASSIGNOR TO INVINCIBLE LAUNDRY EQUIPMENT CO., OF CHICAGO, ILLINOIS, A CORPORATION OF ILLINOIS

OSCILLATING WASHER

Application filed April 4, 1927. Serial No. 180,649.

This invention relates to a washing machine of the oscillating type and it is an object of this invention to provide such a machine embodying a plurality of tubs which are simultaneously operated in a novel manner, and means for simultaneously draining said tubs, which means is not rendered effective by the oscillations of the tubs.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views;

Figure 1 is a top plan view of the washing machine involving this invention.

Figure 2 is a reduced left hand end elevational view of the machine.

Figure 3 is a reduced right hand end elevational view of the machine.

Figure 4 is a sectional view taken substantially upon the line IV—IV of Figure 5 with parts in elevation.

Figure 5 is a part sectional and part elevational view of the machine; the section being taken in a vertical plane.

Figure 6 is an enlarged fragmentary sectional view taken in a vertical plane through the lower portion of the left hand end tub illustrating the drain valve and operating means therefor.

Figure 7 is an enlarged fragmentary sectional view illustrating the oscillating drive for the tubs.

Figure 8 is an enlarged fragmentary part sectional and part elevational view showing the drain valve operating mechanism taken upon the line VIII—VIII of Figure 5.

Figure 9 is a sectional view upon the line IX—IX of Figure 5.

Figure 10 is an enlarged sectional view taken upon the line X—X of Figure 6.

As shown on the drawings:

Referring to the drawing which illustrates the preferred embodiment of this invention, it will be noted that the machine is supported upon a suitable base structure which consists

of spaced leg members 1. Each leg member 1 is bifurcated at its bottom to provide separate feet 2. Between the leg members 1 there extend a pair of channel bars 3 which are fastened to the bottom of the leg members. This base structure supports the various parts of the machine as will later more fully appear.

The wash tubs, which are three in number and which are represented by the references A, B, and C, are supported upon an oscillatable cradle generally denoted by the reference 4 and which cradle is provided with end trunnions 5 (Figures 5 and 6) swiveled in the end members. This cradle consists of a number of parts which will be more fully described. The cradle 4 comprises the end castings or brackets 4^a (Figures 2 and 3) upon which the aforementioned trunnions 5 are formed. A pair of parallel and longitudinally extending angle members 6 connect the two castings, and these angle members 6 carry castings 7, one beneath each tub. The general transverse configurations of the castings are best shown in Figures 4 and 7 and in referring to said figures, it will be noted that each casting 7 has a pair of right angles 8 in its bottom for fitting over the longitudinal angles 6. The depending flanges of the angles 6 are bolted or secured to the casting. The base of each right angle 8 is provided with an upwardly sloping arm 9 provided with a lug 10 for a purpose that will later appear. These castings 7 are also provided with horizontal portions 11 upon which the tubs rest.

Each tub is oblong in cross section and is provided with a hinged door 13 at its top. Adjacent the upper and lower margins of the door, the adjacent edges of the tubs are provided with ears 14 (Figure 1) whereby a pair of ears are formed between the tubs. A metal strap or band 15 is secured at one end to each pair of ears 14 by a suitable bolt. The other end of each strap is provided with an outstanding lug 16 (Figure 4) which is adjustably bolted to one of the lugs 10. These straps serve to anchor the tubs to the cradle.

The longitudinal configuration of the castings 7 are shown in Figure 6. It will be

noted that the portion 17 under the tub has a dished shaped contour which is provided with an opening 18 to a valve housing 19 which is integrally formed with the casting 7. 5 A hollow conical valve 20 is adapted to rotate in this housing for controlling the inlet port 18. The valve housing 19 at its discharge end communicates with a drain pipe 21. A cylindrical sealing member 22 rotatably 10 mounted in the drain pipe 21 is attached to the end of the valve housing to convey the fluid from the valve housing to the drain pipe. The bottom of the tub is perforated above the dished portion, as indicated at 23, 15 to allow the washing fluid to drain into the valve.

The axis of the valve 20 lies in the axis of the end trunnions 5 which is the pivot axis about which the tubs oscillate and may be 20 termed the axis of oscillation. It will be understood that each of the tubs is provided with such a drain valve and they all have a common axis which lies in the axis of the end trunnions of the cradle or the axis of oscillation. Consequently, during the oscillations 25 of the wash tubs, the sealing member 22 will rotate and oscillate in its bearing in the drain pipe.

All the drain valves are adapted to be simultaneously operated to their open or closed position by a manually rotatable shaft 24 at one end of the machine. This shaft is provided with a transverse operating handle 25 at its upper end. In order to support the 30 shaft 24, it is journaled at its lower end in a hollow casing 26 attached to the leg member 1. The upper end of the shaft 24 extends through a free block 27 which is held in position by a pair of parallel rods 28 secured at 35 their lower ends in the hollow housing 26. The upper ends of the rods 28 extend into the free block 27, one being located upon each 40 side of the shaft 24.

The lower end of the aforesaid shaft 24 has 45 a beveled pinion 29 (Figure 6) secured thereon. This pinion meshes with a beveled gear 30 pinned on a shaft 31 which is journaled in the trunnion 5 of the end bracket 4 and extends therethrough. The inner end of the 50 shaft 31 is provided with an arm 32 having a laterally projecting lug 33 adapted during rotation of the shaft 31 for engaging a somewhat similar lug 34 on a bifurcated arm or crank 35 which is secured to a stem on the valve 20. A link 37 is connected at one end 55 between the bifurcated parts of arm 35. The other end of this link 37 is connected to a crank arm 38 (Figure 8) secured to a shaft 39 which is journaled in the casting 7 and extends therebeyond to the valve in the tub C.

The valve in the intermediate tub B and the valve in the right end tub C are simultaneously operated with the first valve in the tub A through suitable connections with the 60 shaft 39. The form of connection is shown

in Figure 8 and in referring to said figure it will be observed that there is a crank arm 38 on the shaft 39 adjacent each of said valves, which is connected by a link 37 with the bifurcated crank 35 on the valve stem. 70

During the oscillations of the tubs the shaft 39 will, of course, be subject to oscillations, but the valves 20 will not be actuated for the reason that they also oscillate with the tubs. It is the valve arms 35 that cause the oscillation of the shaft 39, which merely rotate in accordance with the oscillatory movement of the valve with its housing. However, when the tubs are at rest the rotation of the shaft 24 will rotate the first valve and cause the rotation of shaft 39 which through the crank arms 38, links 37, and arms 35 will actuate the other valves in the tubs B and C. 80

The mechanism for oscillating the cradle that supports the tubs is shown in Figures 5 and 7 and the same consists of a motor 40 which is secured on a platform 41 secured to one leg member 1. The motor shaft is geared to a spur gear 42 (Figure 5) secured upon a shaft 43 journaled in the end leg member 1. 85 The inner end of the shaft 43 is journaled in a gear casing 44 on the angle members 3 and carries a beveled pinion 45 within the gear casing. The pinion 45 meshes with a horizontal gear 46 journaled upon a stub shaft 47 secured in the bottom wall of the casing. An obliquely arranged shaft 48 is fixed at its lower end in an inclined socket 49 in the body of the gear 46. This shaft extends through a circular opening 50 in the top of the gear 100 casing and through a radial slot 51 in a rotatable disk 52 journaled upon the end of the shaft 47. This disk serves to close the circular opening 50 in the top of the gear casing and protect the gear. The upper end of the shaft 48 is secured to a yoke 53, the ends of which are journaled or pivoted upon a shaft 54, the ends of which are secured in suitable bosses 55 on the adjacent casting 7. 105

It will be obvious that as the gear 46 is rotated it will carry the shaft 48 therewith, the pivotal connection of the yoke 53 on shaft 54 allowing the lower end of shaft 48 to bodily move in the arc of a circle. The rotation of the gear 46 will consequently cause the cradle 110 and tubs thereon to oscillate as shown in Figure 7.

Hot and cold water may be simultaneously supplied to the tubs through a supply pipe 56 (Figure 5) which has a lower horizontal leg or bend 57 which is retained in a suitable packing 58. This horizontal bend is rotatably coupled to a pipe line 59 (Figure 1) extending along one side of the tubs and suitably attached thereto. This pipe line is provided with suitable faucets 60 extending into the various tubs. As the tubs are oscillated, the pipe line 59 which oscillates with the tubs will rotate relatively to the horizontal bend 57 on the supply pipe 56. 120 125 130

Each door 13 of the different tubs is adapted to be latched in closed position by a rotatable latch 61 which engages under suitable lugs 62 on the top of the tubs. These rotatable latches are each provided with a notch 63 which may be brought into registry with the locking lugs for the purpose of unlatching the door. The doors and tubs may be provided with coacting stops 64 and 65 which come into abutting relation when the doors are opened for supporting the same in open position. From the foregoing, it will be apparent that a novel washing machine involving a plurality of separate tubs simultaneously operable has been provided, and in which the drains are simultaneously operable, and in which the oscillations of the tubs do not operate the drain connections sufficiently to open the drain valves. It will be appreciated that providing a plurality of tubs in one machine, the clothing may be classified, different kinds of garments need not be mixed and in some instances the garments of different customers need not be mixed; besides different cleansing agents may be put in the different tubs as required.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

35 1. In a machine of the class described, spaced supports, a cradle having end trunnions journaled in said supports, a tub secured to said cradle, a yoke pivoted to said cradle, an inclined shaft connected to said 40 yoke, and a horizontal gear connected to said inclined shaft and means for rotating said gear.

2. In a washing machine, a rockable cradle having an axis of oscillation, a plurality of 45 tubs supported upon said cradle, said tubs having drain valves in the axis of oscillation, and means for simultaneously operating said valves.

3. In a washing machine, an oscillatable cradle having an axis of oscillation, a plurality of tubs upon said cradle, each tub having a valve with an axis located in the axis of oscillation of said cradle, a rotatable shaft, operating mechanism connecting said valves, 55 and shaft, and manually operated means for actuating said shaft.

4. In a washing machine, a cradle having an axis of oscillation, a plurality of tubs upon said cradle, each tub having a drain valve 60 located in said axis of oscillation, an arm on one valve, a manually operated means including an arm adapted for releasably engaging the first arm for actuating said valve, and means connected with said first arm for actuating the other valves.

5. In a washing machine, a plurality of tubs having a common axis of oscillation, each tub having a rotary valve in said axis of oscillation, said valves being interconnected for simultaneous actuation, and means unaffected by the oscillation of said tubs for actuating said valves.

In testimony whereof I have hereunto subscribed my name at Chicago, Cook County, Illinois.
